SADIRON HOLDER

Howard A. Perrigo, Hamden, Conn.

Application December 31, 1947, Serial No. 795,087

4 Claims. (Cl. 248—117.1)

1

The present invention relates in general to sadiron holders and more especially to a holder of the type adapted to be secured to a wall or similar vertical supporting structure for holding an iron when not in use.

An object of the invention is to provide an improved iron holder of superior construction and relatively inexpensive but durable parts.

A further object of the invention is to provide an improved iron holder embodying adjustable means for adapting the holder to irons of different sizes.

A still further object of the invention is to provide an adjustable iron holder comprising a wire-frame and a face plate secured thereto by superior supporting-means.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a front elevation in perspective of the improved iron holder of this invention, the adjustable harness of the holder being shown in its lowermost position by full lines and in its uppermost position by broken lines;

Fig. 2 is a side elevation of the iron holder of Fig. 1 in which two irons of different sizes are shown by broken lines mounted in the holder; and

Fig. 3 is a fragmentary elevation of one edge of the face plate of the holder on section line 3—3 of Fig. 1 showing one of the improved frame-supporting posts.

Referring to the drawings which show an exemplary embodiment of the invention, the holder is of the type designed to be secured to a vertical support such, for example, as a wall *w* indicated by broken lines in Fig. 2 and comprises an imperforate plate 8 consisting of a heat insulation material such as fiber board or an equivalent material having generally the shape of the sole of an iron, but somewhat larger so as to provide a marginal portion 9 around the perimeter of the plate. Mounted in the marginal position of the plate is a plurality of posts, as indicated generally at 10, which posts extend outwardly substantially perpendicularly from the front face of the plate 8 and are adapted to support the wire-frame of the holder, as hereinafter described. Each post comprises preferably a cotter pin 11 with a spacer-sleeve 12 and washer 13 assembled

2

on its respective cotter pin, in the manner shown in Fig. 3, the eyelet of each cotter pin being supported thusly a predetermined distance above the front or upper face of the plate 8. The split end 14 of each cotter pin is spread apart on the underside or back of the plate 8 with a washer 15 interposed between the back of the plate and the spread-apart ends of each respective cotter pin. In the preferred embodiment, six posts are used, two on opposite sides respectively of the plate 8 adjacent the base thereof, two on opposite sides respectively of its nose-portion and two on opposite sides respectively of the plate intermediate its nose- and base-portions.

The wire-frame of the holder is indicated generally at 16 and comprises a frame 17 fixedly supported in the eyelets of the respective cotter pins 11; and a movable frame or harness 18 slidably mounted on the fixed frame 17. The latter is symmetrical with and conforms generally to the perimeter of the plate 8 and comprises convex wire side-rails 19, convex wire nose-rails 20 and substantially-straight wire guide-rails 21 intermediate the convex side- and nose-rails. The upper ends of the nose-rails 20 are joined together adjacent the apex of the plate 8 to form a single reach 22 which extends beyond its apex, the forward end of the reach 22 being bent down or back at substantially right angles to form a leg 23, which in turn is formed with an eyelet 24 at substantially right angles thereto for attaching the holder to the vertical supporting surface *w*. It is preferred that the length of the leg 23 be such that the plate 8 of the holder will be held outwardly away from contact with the supporting surface *w* when the holder is attached thereto, as hereinafter described. The lower end of each convex side-rail 19 is bent down and then doubled back on itself to form a leg 25 which is substantially equal in length to the leg 23 and is provided with a right-angled eyelet 26 for securing the lower end of the frame to the supporting wall. Each side-rail 19 is extended, by a substantially-straight reach, from its leg 25 across to the opposite side of the frame to form a base-rail 27, the two base-rails 27 of the corresponding side-rails 19 crossing over each other intermediate the opposite ends thereof, as indicated clearly in Fig. 1. When the iron is supported in the holder, as indicated by broken lines in Fig. 2, these base-rails 27 provide supporting-means for the rear end of the iron. In order to reinforce and to give rigidity to these supporting base-rails, the latter may be fastened together at

their point of intersection. Each base-rail has an extension which is bent down at substantially right angles to its respective reach 27 and in the plane of the frame 17, as indicated at 29, and is then bent up and back upon itself to form an open loop 30, the free end 31 of which is bent over at substantially right angles to the vertical plane of the loop and extended back transversely of the frame to join the free end 31 of the extension 29 of the corresponding reach 27, the two free ends being joined by a soldered joint or equivalent fastening-means to form a rack for supporting the coiled ironer-cord 33, as indicated by the broken lines in Fig. 2.

The movable frame or harness 18 of the holder comprises a pair of arms 34, each having an eyelet 35 at its outer free end adapted to engage and slide freely on the corresponding straight guide-rail 21 of the fixed frame, each arm 34 being bent to extend upwardly and inwardly toward the center of the frame and outwardly with respect to the vertical plane thereof, as seen in Figs. 1 and 2. The inner end of each arm 34 of the harness is bent at an angle such as to lie substantially parallel to the longitudinal axis of the frame 17 and form a forwardly-extending reach 36 which is arranged in parallel-engaging relationship with the reach 36 of the opposite arm 34 of the harness, the two reaches terminating at their forward ends in a common eyelet 37. The latter is bent down at a slight angle with respect to the aforesaid reaches 36 and is suitably dimensioned so as to slide freely along the reach 22 of the fixed frame 17. Thus, the harness 18 is adapted to slide up and down on the fixed frame, the extent of its movement being substantially equal to the length of the straight guide-rails 21 of the fixed frame.

The holder is adapted to be secured firmly to the vertical supporting surface *w* by screws or equivalent fastening-means (not shown) engaged in the eyelets of the legs 23 and 25 respectively of the fixed frame, to support the plate 8 of the holder in spaced substantially-parallel relationship to the supporting surface. The iron 33 is placed in the holder by inserting the nose of the iron beneath the harness 18 and sliding the iron, including the harness 18, upwardly until the rear end of the iron is in front of the supporting base-rails 27 of the fixed frame and engaged against the front face of the plate. Thereafter, the iron is seated against the supporting base-rails 27, the harness 18 simultaneously sliding back freely with the iron so as to hold its nose from swinging outwardly away from the frame. For relatively-small irons, the harness 18 will drop down substantially to the position shown by the full lines in Fig. 2, while for a longer iron, the harness 18 will automatically adjust itself to a position higher upon the fixed frame, as indicated by the broken lines in Fig. 2.

For either extreme, the harness and more especially the fork thereof formed at the intersection of its two arms 34, engages the nose of the iron at a high point thereon where the curvature of the nose blends into the substantially-flat upper surface of the iron body, as shown especially well in Fig. 2, and consequently will effectively hold the nose of the iron down against the plate 8 without the use of supplementary resilient or equivalent holding-means.

From the foregoing description it will be seen that the improved holder is of exceedingly simple construction and embodies relatively few parts which are durable and economical to manufac-

ture; and that the improved holder is automatically adjustable to irons of various sizes.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An iron holder comprising: a wire-frame having legs arranged to secure said frame in spaced relationship on a substantially-vertical support; a transverse base-rail at the lower end of said frame; longitudinal guide-rails intermediate the upper and lower ends of said frame; an imperforate heat insulating plate; means to suspend said plate intermediate said vertical-supporting surface and the vertical plane of said frame; and a harness comprising forked arms arranged to extend across said plate, the outer free ends of said arms being slidably mounted on the longitudinal guide-rails of said wire-frame, said harness being adapted thereby to hold the nose of an iron supported in said frame against said transverse base-rails against said imperforate plate and to automatically adjust itself to irons of different sizes mounted in said wire-frame.

2. An iron holder comprising: a wire-frame having integral legs provided with eyelets for securing said frame in spaced relationship on a substantially-vertical support; a transverse base-rail at the lower end of said frame; a longitudinal guide-rail on opposite sides respectively of said frame intermediate the upper and lower ends thereof; an imperforate heat insulating plate; posts secured to said plate and to said frame for suspending said plate beneath said frame; and a wire harness comprising forked arms having eyelets at the outer ends thereof respectively arranged to slidably engage the respective longitudinal guide-rails of said frame to slidably mount said harness thereon said harness being arranged to engage the nose of an iron supported in said frame against said base-rail to hold the nose of said iron against said imperforate plate and to automatically adjust itself to irons of different sizes.

3. An iron holder comprising: a wire-frame having integral legs provided with eyelets for securing said frame in spaced relationship on a substantially-vertical support; a reach extending longitudinally from the apex of said wire-frame; a transverse base-rail at the lower end of said frame; a longitudinal guide-rail on opposite sides respectively of said frame intermediate the upper and lower ends thereof; an imperforate heat insulating plate; posts secured to said plate on opposite sides thereof respectively and to corresponding sides of said frame for suspending said plate beneath said frame intermediate said supporting surface and the vertical plane of said frame; and a wire harness comprising forked arms having eyelets at the outer ends thereof respectively arranged to slidably engage the respective longitudinal guide-rails of said frame, and a forwardly-projecting reach having an eyelet arranged to slidably engage the reach of the said frame to slidably mount said harness thereon said harness being arranged to engage the nose of an iron supported in said frame against said base-rail to hold the nose of said iron against

said imperforate plate and to automatically adjust itself to irons of different sizes.

4. An iron holder comprising: a wire-frame having integral legs provided with eyelets for securing said frame in spaced relationship on a substantially-vertical support; a reach extending longitudinally from the apex of said wire-frame; a transverse base-rail at the lower end of said frame; a longitudinal guide-rail on opposite sides respectively of said frame intermediate the upper and lower ends thereof; an imperforate heat insulating plate; posts secured to said plate on opposite sides thereof respectively and to corresponding sides of said frame for suspending said plate beneath said frame intermediate said supporting surface and the vertical plane of said frame; a wire harness comprising forked arms having eyelets at the outer ends thereof respectively arranged to slidably engage the respective longitudinal guide-rails of said frame, and a forwardly-projecting reach having

5 an eyelet arranged to slidably engage the reach of the said frame to slidably mount said harness thereon, said harness being arranged to engage the nose of an iron supported in said frame against said base-rail to hold the nose of said iron against said imperforate plate and to automatically adjust itself to irons of different sizes; and a rack comprising integral wire loops depending from the bottom of said wire-frame for supporting the iron cord.
